FOREIGN PATENT DOCUMENTS

GB 6236323 * 11/2022

Primary Examiner — George D. Kirschbaum*Assistant Examiner* — Antoinette Martine Suiter(74) *Attorney, Agent, or Firm* — Daniel M. Cohn;
Howard M. Cohn(57) **CLAIM**

The ornamental design for a doorbell base, as shown and described.

DESCRIPTION

FIG. 1 is a perspective view of a doorbell base showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the doorbell base. The dash-dot broken lines in the drawings depict portions of the doorbell base that form no part of the claimed design.
